UNITED STATES PATENT OFFICE.

JOHN L. McGEE, OF DES MOINES, IOWA.

STANDING CONCRETE-POST FORM.

1,119,711.

Specification of Letters Patent.

Patented Dec. 1, 1914.

Application filed July 23, 1913. Serial No. 780,840.

To all whom it may concern:

Be it known that I, JOHN L. McGEE, a citizen of the United States, residing at Des Moines, in the county of Polk and State 5 of Iowa, have invented certain new and useful Improvements in Standing Concrete-Post Forms; and I do hereby declare the following to be a full, clear, and exact description of the invention, such as will enable others skilled in the art to which it 10 pertains to make and use the same.

My invention relates to improvements in concrete post forms, and has particular reference to that type that are adapted to 15 be secured to the ground over the post holes in an upright position prior to the pouring of concrete therein for the purpose of molding the posts.

An important object of my invention is 20 to provide a device of the above mentioned character which consists of a pair of co-acting semi-cylindrical sections constituting the form of my improved construction, and means for anchoring the form in operative 25 position carried by each of said sections.

A further important object of my invention is to provide a device of the above mentioned character which is constructed of few 30 parts, simple and reliable in its operation, and cheap to manufacture.

The above and additional objects are accomplished by such means as are illustrated in the accompanying drawings, described in the following specification, and then more 35 particularly pointed out in the claims which are appended hereto and form a part of this application.

With reference to the drawings, wherein I have illustrated the preferred embodiment 40 of my invention as it is reduced to practice, and throughout the several views of which similar reference numerals designate corresponding parts: Figure 1 is a side elevation illustrating the form in assembled position. Fig. 2 is a vertical sectional view illustrating 45 the form in operative position over the post hole and showing the concrete therein partly in section to illustrate the reinforcing elements embedded in the concrete. Fig. 3 is a transverse sectional view taken on line 3—3 50 of Fig. 1 and illustrating the hinged connection of the sections and the anchoring plates formed thereon, and, Fig. 4 is a detail vertical section of one of the ties embedded 55 in the concrete, for securing the fence wires to the post.

Referring now to the drawings forming a part of this specification and in which like numerals are employed to designate like parts throughout the same, the numerals 1 and 2 designate the semi-cylindrical sections which are slightly tapered toward their upper ends and are hingedly secured at certain of their longitudinal edges by means of a plurality of ears 3 formed in alignment upon the longitudinal edges of each of the sections, and a pin 4 extending longitudinally through each of the ears 3.

Each of the sections 1 and 2 are provided upon their longitudinal free edges with a plurality of outwardly extending tongues 5 which are disposed in spaced relationship to each other to provide a plurality of laterally extending recesses 6. The recesses of each of the sections are adapted to receive the tongues 5 which are spaced from the upper and lower edges of the recesses to provide a plurality of apertures 7 in which a wire tie 8 is adapted to be inserted. The wire ties 8 are inserted within the apertures 7 in such a manner as to allow the free ends thereof to extend outwardly beyond the sections for engagement with the wires of the fence, and the inner terminal of the wire tie 8 is adapted to be embedded or molded within the concrete, which is designated generally by the numeral 9. As a means for locking the section in operative position, this invention employs rings 10 adapted to be mounted upon the sections, as illustrated in Fig. 2, or a plurality of hooks, 85 designated 11 and shown in Fig. 1.

In order to provide for the anchoring of the form in operative position over the post hole, the sections 1 and 2 are each provided with a plurality of spaced radially extending plates 12 each of which is provided with an opening 13 at their outer terminals to facilitate for the insertion of a spike 14 which is adapted to be driven into the ground about the post hole. When it is desired to reinforce the concrete post a plurality of vertically disposed reinforcing rods 15 are mounted within the form in spaced relationship to the sides thereof prior to the pouring of the concrete into the form. The upper terminals of each of the sections 1 and 2 are bent to provide the rounded portions 16 in order to facilitate for the formation of a rounded concrete post, and are recessed to provide an opening 17 when the sections are in operative position.

tion to provide for pouring of the concrete therein.

When reinforcing rods of greater length than the sections and post hole are used, provision is made for the proper spacing of each of the rods, as this invention provides a plurality of notches or recesses 18 arranged in spaced relationship about the opening 17 at the upper terminals of each 10 of the sections that are adapted to receive the rods whereby the desired effect may be had, and when the concrete is poured into the form the rods are driven through the soft concrete and into the post hole and 15 flush with the top of the concrete within the form.

The manner of operating the form in connection with forming the fence posts may be briefly described as follows: The 20 forms are arranged in a line over the fields in which a plurality of post holes have previously been dug, in a vertical position over the post holes, and when it is desired the sections are swung open to allow for the 25 insertion of the reinforcing bars after the manner described, and the sections are locked after the manner described, whereupon the next step is to anchor the sections in operative position over the post hole, and this is done by driving the spikes 14 30 through the openings 13 formed in the plates 12. The concrete is then poured into the top through the opening 17 into the form, and while the concrete is yet soft the 35 wire tires 8 are inserted within the apertures 7 in such a manner as to allow the free ends thereof to extend beyond the sections. In case reinforcing rods of greater length than the post hole and form are used the next 40 step is to drive the rods through the soft concrete into the post hole and ground therebeneath until the upper ends of the reinforcing bars are flush with the top of the concrete within the form. The forms are 45 left standing upon the field until the concrete has hardened sufficiently, and are then removed.

It will thus be seen that a form for concrete posts is provided which will accomplish all the functions hereinbefore cited in a reliable and expeditious manner.

In reduction to practice, I have found that the form of my invention, illustrated in the drawings and referred to in the above 55 description, as the preferred embodiment, is the most efficient and practical; yet, realizing that the conditions concurrent with the adoption of my device will necessarily vary,

I desire to emphasize the fact that various minor changes in details of construction, proportion and arrangement of parts may be resorted to, when required, without sacrificing any of the advantages of my invention, as defined in the appended claims.

Having thus fully described my invention, what I claim is:

1. A form for concrete fence posts comprising a pair of semi-cylindrical sections, said sections being hinged adjacent certain of their longitudinal edges, a plurality of spaced tongues formed upon the free longitudinal edge of one of said sections, the other of said sections being provided with a plurality of laterally extending recesses at its free longitudinal edge, said tongues inserted 75 within said recesses and being smaller than said recesses and adapted to hold a wire tie between said tongues, said sections having their upper extremities rounded and provided at the edges thereof with spaced inwardly extending recesses.

2. A form for concrete fence posts comprising a pair of semi-cylindrical sections, said sections being hinged adjacent certain of their longitudinal edges, a plurality of spaced tongues formed upon the free longitudinal edge of one of said sections, the other of said sections being provided with a plurality of laterally extending recesses at its free longitudinal edge, said tongues inserted 85 within said recesses and being smaller than said recesses and adapted to hold a wire tie between said tongues, said sections having their upper extremities rounded and provided at the edges thereof with spaced 90 inwardly extending recesses, and means for locking the sections in assembled position.

3. A form for concrete fence posts comprising a pair of semi-cylindrical sections, spaced tongues formed on one longitudinal 100 edge of one of said sections, spaced recesses formed on one longitudinal edge of the other of said sections, a plurality of integrally formed laterally extending spaced securing flanges formed on the lower portions of each of said sections, said sections being rounded at their upper extremities, the edge of said rounded portions being provided with recesses and means for locking the sections in assembled position.

In testimony whereof I affix my signature in presence of two witnesses.

JOHN L. McGEE.
